(57) **CLAIM**

The ornamental design for a lavalier wireless microphone, as shown and described.

DESCRIPTION

FIG. 1 is a perspective view of a lavalier wireless microphone showing my new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of a portion indicated with numeric 9 in FIG. 2; and,

FIG. 10 is a perspective view thereof in an alternate position. The broken lines shown in the drawings represent portions of the lavalier wireless microphone that form no part of the claimed design. The dash dot dash broken lines shown in FIG. 2 and FIG. 9 are for the purpose of depicting areas of enlargement and form no part of the claimed design.
